BOLT EJECTOR FOR THREAD ROLLERS

Louis J. Mitchell, Cleveland, Ohio, assignor, by
mesne assignments, to Jack & Heintz Precision
Industries, Inc., Cleveland, Ohio, a corporation
of Delaware

Application June 16, 1945, Serial No. 599,778

2 Claims. (Cl. 80—8)

1

This invention relates in general to automatic metal working machines and more particularly to automatic work ejecting means for thread rolling machines.

In thread rolling machines it is common practice to have one threaded die adjustably secured to the stationary frame of the machine and to have a complementary threaded die adjustably secured to a movable carriage which latter is adjustable to bring its threaded die into predetermined spaced parallel relationship with the stationary die, the carriage being automatically driven back and forth parallel with the frame at a predetermined speed and length of stroke at least equal to the length of one of the dies. The work may comprise an unthreaded bolt which is fed into the space between the dies at the start of the stroke of the movable driven die. The bolt is compressed between the dies and rotatably carried to the opposite end of the stationary die by the driven die while the bolt is having a spiral screw thread pressed thereto. It is of utmost importance that the bolt be positively ejected at the completion of this forward stroke. Failure of such ejection results in the bolt being carried back between the dies on the back stroke and a consequent ruining of the bolt and, more important, the damaging of both of the expensive threaded dies. Experience has shown that gravity alone or inefficient makeshift ejection devices lacking in positiveness cannot be relied upon for the highly important feature of ejection.

It is, therefore, one of the primary objects of the present invention to provide such a positive automatic work ejecting device whose action is so correlated between the relative movements of the two relatively movable threaded dies that it will remain out of the path of the bolt during its forward travel between the dies and be actuated at a predetermined point in such travel to follow the bolt and moreover contact the latter in full length flatwise engagement to positively eject the threaded bolt at the very end of the stroke just prior to the start of the back stroke.

With the foregoing and other objects in view, the invention resides in the combination of parts and in the details of construction hereinafter set forth in the following specification and appended claims, certain embodiments thereof being illustrated in the accompanying drawings, in which:

Figure 1 is a view in perspective of a portion of a thread rolling machine showing one threaded die carried by the stationary frame and another carried by a reciprocating carriage showing the adjustable bracket for supporting the work eject-

2

ing device carried by the frame and showing the carriage in the midst of its work threading stroke;

Figure 2 is a similar view with the frame broken away to show the position of the work ejecting device in inoperative horizontal position at the start of the forward stroke of the carriage;

Figure 3 is a view similar to Figure 2 near the completion of the forward stroke of the carriage showing the work ejecting lever raised from its previous horizontal position to a vertical position to eject the work at the completion of the stroke;

Figure 4 is a detail view in elevation of a double land bolt after spiral threads have been pressed therein;

Figure 5 is an enlarged detail view in side elevation of the work ejection device in the vertical position and taken along line 5—5 of Figure 3;

Figure 6 is a view similar to Figure 5 showing the work ejection device in inoperative horizontal position and taken along line 6—6 of Figure 2; and

Figure 7 is an enlarged detail end view of the bracket for supporting the work ejecting device.

Referring more particularly to the drawings, the stationary frame 1 has adjustably secured thereto a block 9 to which is secured by a suitable bracket 2 and bolt 3 a thread die 4. Mounted slidably on the frame is a carriage 5 that also has adjustably secured thereto by a suitable bracket 6 and bolt 7 a thread die 8. The two opposed faces of the thread dies are so threaded as to press the work, such as a bolt, to form a continuous spiral screw thread as it is rolled by the relative longitudinal parallel movement of the die faces which engage the bolt. The adjustability of the two dies, in accordance with usual practice, should be such as to permit vertical longitudinal and lateral adjustment to respectively adjust alignment of threads, effective length of reciprocatory stroke of the carriage and the space between the threaded faces for different thicknesses of work to be engaged between the threaded faces.

The work ejecting device is carried by a bracket 10 having a pair of elongated slots 11 to receive bolts 12 to adjustably secure the bracket to the stationary frame 1. This bracket has pivotally secured to its other end at 13 the work ejecting lever 14. Lever 14 carries a pin 15 that rides on a ledge 16 of the carriage 5 below its die 8. Bracket 10 has a pin 17 around which is hooked one end of a tension coil spring 18 whose other end is hooked to lever 14 below pin 13.

Figure 2 shows the relative positions of the car-

riage 5 and the lever 14 prior to the beginning of the forward stroke of the carriage. The lever 14 is horizontal as pin rests on ledge 16 of the carriage well below the lower edge of the carriage die 8, as well as that of the base die 4. It is at this point in the sequence of operation that the work such as a bolt 19, shown in Figure 4 as having two spaced lands 20 and 21, is inserted in a vertical attitude between the front portion of the carriage die 8 and the rear portion of the base die 4. Prior to such insertion the lands are unthreaded and have a smooth exterior surface.

Forward movement of die 8 carries the bolt forwardly as the latter is compressed and rotated in engagement with the threads of the two dies 8 and 4. During the major portion of the forward travel of carriage 8 the bolt ejecting lever 14 remains in its horizontal position of Figure 2 completely out of the path of travel of the bolt between the two thread dies. At practically the completion of the forward stroke of the carriage its rear vertical ledge 22, which is in alignment with the rear edge of die 8, engages pin 15 of the ejecting lever. This rocks lever 14 in a counterclockwise direction from its horizontal position of Figure 2 to its vertical position of Figure 3 about its pivot 13 against the action of tension coil spring 18. The height of lever 14 is preferably sufficient to extend at least to the top edges of the dies and consequently engages a substantial portion of the length of the bolt, if not all except the bolt head. This timed action of the ejecting lever 14 insures a positive ejection of the bolt after it has had its spiral threads pressed into its lands, as shown in Figure 4.

It follows that the backstroke which starts immediately after the ejection of the bolt removes the pressure of wall 22 upon pin 15. Consequently spring 18 exerts its force to rock lever 14 counterclockwise about pin 13 from a vertical position of Figure 3 back to its horizontal inoperative position of Figure 2 as the two thread dies are in position to receive another bolt for another threading operation.

I claim:

1. In combination with a thread rolling machine having a pair of dies with opposed threaded

faces one of which is carried by a stationary frame and the other by a carriage reciprocably movable parallel therewith in spaced relation to receive therebetween a bolt to be carried forward by the forward stroke of said carriage as the bolt is rolled and compressed to have a continuous spiral screw thread pressed therein by the threads of said dies, a device for ejecting said bolt upon completion of the forward stroke of the carriage and prior to the start of the backstroke thereof, said ejecting device comprising an adjustable bracket carried by said frame and carrying a pivoted lever operable within a plane lying between said die faces and normally maintained horizontal and below the lower edges thereof, means on said lever engageable by said carriage near the end of its forward stroke for operating said lever to swing it into a vertical position to engage the major portion of said bolt in flatwise contact from the rear to positively eject the same.

2. In combination with a thread rolling machine having a pair of dies with opposed threaded faces one of which is carried by a stationary frame and the other by a carriage reciprocably movable parallel therewith in spaced relation to receive therebetween a bolt to be carried forward by the forward stroke of said carriage as the bolt is rolled and compressed to have a continuous spiral screw thread pressed therein by the threads of said dies, a device for ejecting said bolt upon completion of the forward stroke of the carriage and prior to the start of the backstroke thereof, said ejecting device comprising an adjustable bracket carried by said frame and carrying a pivoted lever operable within a plane lying between said die faces and spring means for normally maintaining said lever horizontal and below the lower edges of said dies, a pin carried by said lever to be engaged by a groove in said carriage and adapted to be forced by the rear end of said groove near the completion of the forward stroke of the carriage to rock the lever about its pivot against the action of said spring into a vertical attitude and into flatwise contact with the length of the bolt to positively eject the same.

LOUIS J. MITCHELL.
